INVENTOR

John E. Bickford

UNITED STATES PATENT OFFICE.

JOHN E. BICKFORD, OF WHITMAN, MASSACHUSETTS.

PEG-CUTTER FOR HORNS OF PEGGING-MACHINES.

SPECIFICATION forming part of Letters Patent No. 703,951, dated July 1, 1902.

Application filed January 6, 1902. Serial No. 88,693. (No model.)

To all whom it may concern:

Be it known that I, JOHN E. BICKFORD, of Whitman, in the county of Plymouth and State of Massachusetts, have invented a new § and useful Improvement in Peg-Cutters for Horns of Pegging-Machines, of which the following, taken in connection with the accompanying drawings, is a specification.

My invention relates to a device to be used 10 in connection with the horn of a pegging-machine; and it consists in the peculiar construction and arrangement of the parts, which may be best understood by reference to the description and drawings.

15 The object is to make a compact and exact working device that will admit of a small tip to the horn. This object I attain by means of the mechanism shown in the accompanying drawings, in which—

20 Figure 1 is a view showing portions of the upper part of the standard of a pegging-machine, also the horn and parts of the working mechanism in elevation. Fig. 2 is a vertical section showing the upper end of the horn, 25 the cutting-knife, and a part of the knife-operating bar. Fig. 3 is a horizontal section looking upward, taken on line 3 3 of Fig. 1. Fig. 4 is a vertical section taken on line 4 4 of Fig. 1.

30 In the drawings I have shown the parts of a pegging-machine to which my peg-cutting device has a direct relation, all other parts being omitted. Parts of the standard are indicated in Fig. 1 by A and by A'. In the upper 35 part A' of the standard a part B of the main shaft of the machine is shown. This shaft has a beveled gear C, which drives a corresponding gear C' on the upright shaft D. To the lower end of the shaft D a spur-gear D' is 40 attached. This spur-gear D' engages with the cylindrical gear D², which in turn engages with the spur-gear D³, which rotates freely on the horn-shaft S and has upon its under side a cam projection d, the use of which will be 45 explained hereinafter.

The horn H' H² has a cylindrical base H, which rotates freely on the horn-shaft S. The horn-shaft S has a vertical motion of which the horn partakes, but it does not rotate. The 50 said horn-shaft is forced upward by a weight or spring and is drawn down by a foot-lever. These parts are not shown, as they are of or-

dinary construction and well known. When the horn is drawn down for the purpose of putting on or taking off a shoe, the gear D³ 55 moves with it, but is always in engagement with the cylindrical gear D².

The peg cutter or knife K (see Fig. 2) is made with a cutting edge at its upper end, which in coming in cutting contact with the peg moves forward and upward, cutting through the peg and at the same time working upward, pressing hard against and slightly into the surface of the leather of the sole of the shoe, the edge of the moving knife moving above the fixed knife h, as shown in Fig. 2. The knife h may be made as a part of the tip of the horn, or a flat steel plate may be fastened to the tip of the horn and the fixed knife-edge be made in it, and as the said plate wears it may be removed and repaired or a new one substituted for it. The lower end K' of the knife terminates in a round boss, which fits in a socket made in the upper end of the knife-operating bar K². (See Figs. 1 and 2.) 75 The upper end of the knife-operating bar has a slot in which a fixed pin K³ acts as a guide for the said bar. The lower end of the knife-operating bar is pivoted to a lever K⁴, which swings on a fulcrum-pin at K⁵ and is operated 80 by a rod L and spring L². The upper end of the rod L is provided with lock-nuts L' L', which act as adjusting-nuts. The lower end of the rod L has a cross-arm L³ (see Fig. 4) attached to it. At each end of the cross-arm an anti-friction-roll L⁴ is placed. These antifriction-rolls rest upon the under side of the spur-gear D³ and as the said gear rotates turn on their axis without effecting any movement of the rod L, except when the cam projections d on 90 the under side of said gear come in contact with one of the rolls L⁴. Then the roll will be forced downward, taking the cross-arm L³ and the rod L with it. This action will cause the lever K⁴ to throw up the knife-operating bar 95 K², giving motion to the knife K and cutting off the peg. By forming the hinged connection between the knife K and the knife-operating bar K² by means of a boss and socket I avoid the use of weak parts and have a knife 100 that is readily attached and detached.

I claim—

In a rotating-horn pegging-machine; a peg-cutting knife adapted to move forward to

ward and over the edge of a stationary knife, thereby pressing into the leather of the shoe, whereby the peg is sheared from the surface of the said leather; and mechanism for operating said knife; a stationary knife adapted to coöperate with the moving knife, substantially as and for the purpose set forth.

5 In testimony whereof I have signed my

name to this specification, in the presence of two subscribing witnesses, on this 3d day of 10 January, A. D. 1902.

JOHN E. BICKFORD.
